COMBINED REUSABLE EQUIPMENT TRANS- PORTER AND STORAGE MODULE

Josiah M. Barr, Manhattan Beach, Calif., assignor to
Hughes Aircraft Company, Culver City, Calif.

Filed Feb. 11, 1974, Ser. No. 441,687

Term of patent 14 years

Int. Cl. D9—04

U.S. Cl. D9—246

Fig. 1.

Fig. 2.

Fig. 3.

Fig. 4.

Fig. 5.

Fig. 6.

FIG. 1 is a perspective view of a combined reusable equipment transporter and storage module showing my new design;

FIG. 2 is a fragmentary sectional view taken along the line 2—2 of FIG. 1;

FIG. 3 is a side elevational view on a reduced scale, the opposite side being the same in appearance;

FIG. 4 is an elevational view looking from the right of FIG. 3, the opposite side being the same in appearance;

FIG. 5 is a top plan view; and

FIG. 6 is a bottom plan view thereof.

I claim:

The ornamental design for a combined reusable equipment transporter and storage module, as shown and described.
